UNITED STATES PATENT OFFICE.

JOHN JIRASEK, OF NEWARK, NEW JERSEY.

FLYING-MACHINE OR AEROPLANE.

1,045,850.

Specification of Letters Patent. Patented Dec. 3, 1912.

Application filed August 16, 1911. Serial No. 644,387.

To all whom it may concern:

Be it known that I, JOHN JIRASEK, a subject of the Emperor of Austria-Hungary, residing at Newark, in the county of Essex, 5 and State of New Jersey, have invented certain new and useful Improvements in Flying-Machines or Aeroplanes; and I do hereby declare the following to be a full, clear, and exact description of the invention, such as will enable others skilled in the art to which it appertains to make and use the same, reference being had to the accompanying drawings, and to characters of reference marked thereon, which form a part 10 of this specification.

This invention relates, generally, to improvements in flying machines or aeroplanes; and, the present invention has for its principal object to provide an aeroplane- 20 construction comprising a main frame-work, carrying the motor and propeller and an upright or vertical frame-work also mounted thereon, and in which is supported an oscillatory auxiliary frame, carrying the 25 main plane or main supporting surface.

The invention has for its further object to provide in connection with the frame-work and oscillatory auxiliary frame of the character hereinafter more fully described, 30 an arrangement of independently acting small adjustable frames, carrying the smaller adjusting planes or "ailerons," all with a view of producing a simple, neat, and durable construction, and the parts of which 35 are most compactly arranged in their assembled relations, so as to provide a light and efficiently constructed frame-work, and a flying machine or apparatus which can be readily raised or lowered while in flight, 40 and the directions of its floating movement being under the most complete control of the operator.

Other objects of this invention not at this time more particularly enumerated will be 45 clearly understood from the following detailed description of the present invention.

With the various objects of the present invention in view, the said invention consists, primarily, in the novel flying machine 50 or aeroplane hereinafter set forth; and the invention consists, furthermore, in the novel arrangements and combinations of the several devices and parts, as well as in the details of the construction of the same, all of 55 which will be more fully described in the following specification, and then finally em-

bodied in the clauses of the claim which are appended to and which form an essential part of this specification.

The invention is illustrated in the accompanying drawings, in which:—

Figure 1 is a front view of the general frame-work of a flying machine or aeroplane made according to and embodying the principles of the present invention; and Fig. 65 2 is a top or plan view of the same, the sail or canvas coverings forming the supporting planes being, however, omitted from said views. Fig. 3 is a transverse vertical section, taken on line 3—3 in said Fig. 1, looking in the direction of the arrow α , said view being made on an enlarged scale.

Similar characters of reference are employed in all of the above described views, to indicate corresponding parts.

Referring now to the several figures of the drawings, the reference-character 1 indicates the complete frame-work of a flying machine or aeroplane illustrating one embodiment of the principles of the present invention, the same comprising, in general, a main frame-work consisting of an upper frame in which is suitably mounted the propeller, and a lower and smaller frame depending from said upper frame, in which 80 the motor is placed, for the proper balancing effects, as will presently be more fully described, and which upper frame acts as a support for the oscillatory frame of the main plane or the main supporting surface. 85 The said main frame-work consists, essentially, of a suitably constructed base or platform, as 2, of any suitable dimensions, said base or platform being carried upon and being suitably secured to supporting tubular 90 members 3, arranged preferably in the form of a square or rectangle, said members being suitably connected by means of fittings, as 95

4. Suitably connected with said fittings 4, and extending in upward directions from said fittings, are tubular posts or uprights 5, the front and rear posts or uprights at each side of the frame which is formed by the tubular members 3 being connected by a pair of rods or bars, as 6, said rods or bars 100 being suitably supported and secured in their respective positions by means of nuts 7 and 8 upon each post or upright 5, substantially in the manner illustrated in the several figures of the drawings. Each rod 105 or bar 6 is provided with a suitably formed bearing-portion 9, and suitably mounted in

the said bearing-portions is a rod or shaft 10. Each pair of front and rear posts or uprights; and, the pair of front posts or up-
5 by side-bars, as 11, which are suitably se-
cured at their ends to the respective post or
uprights; and, the pair of front posts or up-
rights, as well as the pair of rear posts or
uprights, are similarly connected and
strengthened by means of rods or bars 12.

- 10 Extending angularly from the fittings 4
at the several corners of the frame, formed
by the tubular members 3, are short members
or arms, as 13, upon the free end-portion of
each of which is a tubular fitting 14, and
15 oscillatorily mounted in each fitting 14 is a
stem 15. The lower end-portion of each
stem 15 is preferably suitably bent, as repre-
sented, and in the forked bearing-portion 16
of each stem 15 is rotatably mounted a wheel
20 17. The purpose of these wheels is well un-
derstood. Each fitting 14 is provided with a
pair of laterally extending short plates or
arms, as 18, between which are arranged and
secured by means of suitable pins or bolts
25 19, the free end-portions of the arm-like
members of a yoke-shaped shock-absorbing
member or element, as 20. Each member or
element 20 is preferably made of a resilient
material, such as rubber, and is of such
30 strength, that the upper and main portions
of said members or elements and against
which the upper end-portions of said stems
15 bear, will readily maintain the parts in
the positions shown in the drawings, and
35 will readily sustain the weight of the flying
machine or apparatus and its load.

Oscillatorily mounted upon the previously
mentioned rod or shaft 10 is the laterally
extending frame of the main plane or main
40 supporting surface of the flying machine or
aeroplane. This frame consists of an ar-
rangement of lower tubular members or ele-
ments, as 21, suitably connected by means of
suitably formed fittings 22, and an arrange-
45 ment of upper tubular members or elements
23, suitably connected by means of suitably
formed fittings 24, the respective fittings 22
and 24 being suitably interconnected by
means of vertical rods or members 25. The
50 planes formed by the said connected lower
members or elements 21, and by the said con-
nected upper members or elements 23, in
practice carry the sail or canvas coverings,
these sail or canvas-coverings, however, be-
55 ing omitted from the drawings herein shown.

Extending from the fittings 22 at the re-
spective pair of centrally located lower tu-
bular members or elements 21, are angularly
disposed braces 26, in the form of tubular
60 rods, said braces being suitably connected
with and secured at their upper end-portions
to suitably formed bearing-plates, as
27, each bearing-plate being provided with
a bearing-portion, as 28, mounted upon the
65 said rod or shaft 10. Suitably connected

with and secured at their lower ends to said
bearing-plates 27 are other angularly dis-
posed braces, as 29, in the form of tubular
rods, said rods having their upper end-ports
70 tions suitably connected with and suitably
secured to the respective fittings 24 of the
respective pair of centrally located upper
tubular members or elements 23. Angular
adjustment of the oscillatorily suspended
75 frame-work thus provided, in either direc-
tion upon the opposite sides of the normally
vertical plane passing through the central
longitudinal axis of the rod or shaft 10, is
produced by means of suitable flexible con-
nections 30, such as sprocket-link chains,
80 wire cables, ropes, or the like.

In the drawings herewith accompanying,
I have shown link-chains, said chains being
suitably secured at their ends to the above-
mentioned lower tubular elements or mem-
bers 21 and passing over sprocket-wheels 31
85 which are rotatably mounted upon the pre-
viously-mentioned rods or bars 12, the said
link-chains 30 passing also under and in
engagement with sprocket-wheels 32 which
90 are suitably secured upon a shaft 33, said
shaft being rotatably mounted slightly above
the previously-mentioned platform or base
2. That the said shaft 33 may receive a ro-
tary motion, in either direction, for the pur-
95 pose of correspondingly moving the link-
chains 30, so as to correspondingly adjust the
frame-work, which carries the main plane
or main supporting surface of the flying ma-
chine, in any angular relation that may be
100 desired, the said shaft 33 has secured there-
on a bevel wheel 34. In mesh with this
bevel wheel 34 is a bevel wheel 35, which is
secured upon a rotary vertical spindle or
shaft 36, and which is provided with a hand-
wheel 37, or other suitably constructed actuating
means, for producing the rotary move-
ments of said spindle or shaft 36.

In connection with the movable or adjust-
able frame-work just described, there is ar-
ranged at each end of said frame-work a
small adjustable plane or aileron.

As will be seen more particularly from
Figs. 2 and 3 of the drawings, each aileron
consists, essentially, of a pair of vertical
rods or members 38 and 39, which are rig-
idly connected with each other by means of
a suitable fitting 40, the said rods or mem-
bers 38 and 39 being permanently secured
at their outer end-portions, by means of the
fittings 41 and 42, respectively, to the lower
tubular end-members 21 and to the upper
tubular end-members 23. Each fitting 40
is made with the oppositely projecting bear-
ing-portions 43 and 44 in which are rota-
bly arranged the end-portions of the re-
spective rods or bars 45 and 46. Rigidly
connected with the end-portions of these
rods or bars 46, by means of suitable fit-
tings, as 47, are the aileron main frames,
120 130

each frame comprising a number of rods or bars 48 which are suitably connected by means of suitable fittings 49. These aileron frames, as will be understood, are of course 5 covered with sail-cloth or canvas. Adjustment of either aileron is made by the operator seated upon a seat, as 50, upon the platform 2 of the machine or apparatus, by means of flexible connections 51, such as 10 sprocket-link chains, cables, ropes, or the like, the free end-portions of each flexible connection, in this case a link-chain being suitably secured to the opposite rods or members 48 of the aileron-frame, then passing 15 upwardly and through links or eyes, as 52, or other suitable means of suspension, connected with the upper end-rods 21, and then forwardly in directions toward the middle of the machine or apparatus, passing 20 downwardly and through other links or eyes, as 52, or other suitable means of suspension, connected with the centrally located upper rods 21, each link-chain passing over and being in operative engagement with a 25 sprocket-wheel 53. Each sprocket-wheel 53 is mounted upon a spindle 54 each spindle being rotatably arranged in a suitable bearing-portion in each side-bar 11, and each spindle 54 being provided with a suitable handle 55, or other operating means, 30 for turning said spindles.

The means for propelling the flying machine is any suitable form of motor, as 56, suitably mounted upon the platform 2, from 35 which is driven by means of a link-chain 57, a propeller-shaft 58, upon the end-portion of which is mounted any suitable construction of propeller, as 59.

The rudder and steering-mechanism is not 40 shown in the accompanying drawings, as any suitable construction of rudder and steering-mechanism may be employed, the same forming no part of my present invention.

45 I am aware, that changes may be made in the arrangements and combinations of the various devices and parts, as well as in the details of the construction of the said parts, without departing from the scope of 50 the present invention as set forth in the foregoing specification, and as defined in the clauses of the claim which are appended to the said specification. Hence, I do not limit my invention to the exact arrangements and 55 combinations of the various devices and parts as described in the said specification, nor do I confine myself to the exact details of the construction of the said parts, as illustrated in the accompanying drawings.

60 I claim:—

1. In a flying machine, a main frame-work provided with means for propelling the machine, standards connected with said main frame-work, cross-bars connected with 65 said standards, bearing-portions connected

with said cross-bars, a shaft mounted on said bearing-portions, a main plane or main supporting surface comprising an open frame-work of rectangular cross-section, angularly disposed tie-rods in said last-mentioned frame-work, bearing-plates connected with said tie-rods, bearing-portions connected with said bearing-plates for pivotally suspending the frame-work of said main plane or main supporting surface from 70 said shaft, a flexible connection connected at its ends with said main plane or main supporting surface, and an actuating means connected with said main frame-work with which said flexible connection co-operates 75 for tilting the entire main plane or main supporting surface, substantially as and for the purposes set forth. 80

2. In a flying machine, a main frame-work provided with means for propelling the machine, standards connected with said main frame-work, cross-bars connected with said standards, bearing-portions connected with said cross-bars, a shaft mounted in 85 said bearing-portions, a main plane or main supporting surface comprising an open frame-work of rectangular cross-section, angularly disposed tie-rods in said last-mentioned frame-work, bearing-portions connected with said bearing-plates for pivotally suspending the frame-work of said main plane or main supporting surface from 90 said shaft, a flexible connection connected at its ends with said main plane or main supporting surface, an actuating means connected with said main frame-work with which said flexible connection co-operates 95 for tilting the entire main plane or main supporting surface, ailerons at the respective ends of the said main plane or main supporting surface, and mechanism between 100 said main frame-work and the said ailerons for tilting said ailerons independently of the said main plane or main supporting surface. 105 substantially as and for the purposes set forth. 110

3. In a flying machine, a main frame-work provided with means for propelling the machine, standards connected with said main frame-work, cross-bars connected with said standards, bearing-portions connected with said cross-bars, a shaft mounted in 115 said bearing-portions, a main plane or main supporting surface comprising an open frame-work of rectangular cross-section, angularly disposed tie-rods in said last-mentioned frame-work, bearing-plates connected with said tie-rods, bearing-portions connected with said bearing-plates for pivotally suspending the frame-work of 120 said main plane or main supporting surface from said shaft, a sprocket-link chain connected at its ends with said main plane or main supporting surface, sprocket-wheels upon said main frame-work over which said 125 130

link-chain passes and is in engagement therewith, and means for actuating one of said sprocket-wheels and causing said link-chain to tilt the entire main plane or main 5 supporting surface, substantially as and for the purposes set forth.

4. In a flying machine, a main frame-work provided with means for propelling the machine, standards connected with said 10 main frame-work, cross-bars connected with said standards, bearing-portions connected with said standards, bearing-portions connected with said cross-bars, a shaft mounted in said bearing-portions, a main plane or 15 main supporting surface comprising an open frame-work of rectangular cross-section, angularly disposed tie-rods in said last-mentioned frame-work, bearing-plates connected with said tie-rods, bearing-portions 20 connected with said bearing-plates for pivotally suspending the frame-work of said main plane or main supporting surface from said shaft, a sprocket-link chain connected at its ends with said main plane or main 25 supporting surface, sprocket-wheels upon said main frame-work over which said link-chain passes and is in engagement therewith, means for actuating one of said 30 sprocket-wheels and causing said link-chain to tilt the entire main plane or main supporting surface, ailerons at the respective ends of the said main plane or main supporting surface, and mechanism between 35 said main frame-work and the said ailerons for tilting said ailerons independently of the said main plane or main supporting surface, substantially as and for the purposes set forth.

5. In a flying machine, a main frame-work provided with means for propelling the machine, standards connected with said main frame-work, cross-bars connected with said standards, bearing-portions connected with said cross-bars, a shaft mounted in said bearing-portions, a main plane or main supporting surface comprising an open frame-work of rectangular cross-section, angularly disposed tie-rods in said last-mentioned frame-work, bearing-plates connected 45 with said tie-rods, bearing-portions connected with said bearing-plates for pivotally suspending the frame-work of said main plane or main supporting surface from said shaft, a sprocket-link chain connected at its 50 ends with said main plane or main supporting surface, sprocket-wheels upon said main frame-work over which said link-chain

passes and is in engagement therewith, a shaft connected with said main frame-work upon which one of said sprocket-wheels is 60 mounted, a bevel-gear upon said shaft, a vertical shaft in said main frame-work, a bevel-gear upon said vertical shaft in mesh with the bevel-gear of said first-mentioned shaft, and a hand-wheel upon said vertical 65 shaft for actuating said shaft and causing said link-chain to tilt the entire main plane or main supporting surface, substantially as and for the purposes set forth.

6. In a flying machine, a main frame-work provided with means for propelling the machine, standards connected with said main frame-work, cross-bars connected with said standards, bearing-portions connected with said cross-bars, a shaft mounted in 75 said bearing-portions, a main plane or main supporting surface comprising an open frame-work of rectangular cross-section, angularly disposed tie-rods in said last-mentioned frame-work, bearing-plates connected 80 with said tie-rods, bearing-portions connected with said bearing-plates for pivotally suspending the frame-work of said main plane or main supporting surface from said shaft, a sprocket-link chain connected 85 at its ends with said main plane or main supporting surface, sprocket-wheels upon said main frame-work over which said link-chain passes and is in engagement therewith, a shaft connected with said main 90 frame-work upon which one of said sprocket-wheels is mounted, a bevel-gear upon said shaft, a vertical shaft in said main frame-work, a bevel-gear upon said vertical shaft in mesh with the bevel-gear of said first- 95 mentioned shaft, and a hand wheel upon said vertical shaft for actuating said shaft and causing said link-chain to tilt the entire main plane or main supporting surface, and mechanism between said main frame-work and the said ailerons for tilting said ailerons independently of the said main plane or main supporting surface, substantially as and for the purposes set forth.

In testimony, that I claim the invention set forth above I have hereunto set my hand this 14th day of August, 1911.

JOHN JIRASEK.
